UNITED STATES PATENT OFFICE

WILLIAM BALLARD, OF NEW YORK, N. Y.

IMPROVED METALLIC DEFENSIVE ARMOR FOR SHIPS.

Specification forming part of Letters Patent No. 35,665, dated June 24, 1862.

To all whom it may concern:

Be it known that I, WILLIAM BALLARD, of the city, county, and State of New York, have invented a new and useful Improvement in the Construction and Armament of Vessels of War; and I do hereby declare that the following is a full, clear, and exact description of the same, reference being had to the accompanying drawings, forming part of this specification, in which—

Figure 1 is an elevation of part of the side of a vessel illustrating my invention. Fig. 2 is a plan view corresponding with Fig. 1. Fig. 3 is a transverse vertical section of the vessel. Fig. 4 is a horizontal section of the same.

Similar letters of reference indicate corresponding parts in the several figures.

This invention consists in a certain novel construction of the frame of and mode of applying armor to vessels, whereby great strength and power of resisting the impact of the projectiles is obtained, and the armor, instead of weakening, is made to strengthen the vessel.

To enable others skilled in the art to make and use my invention, I will proceed to describe its construction and operation.

The framing of the vessel is represented as composed of frames A A, of heavy wrought bar or plate iron, and interposed frames B B, of timber, made severally in the various forms required for the transverse section of the vessel at different points in its length, and preferably of such form as to present an inclined face above the water-line. The iron frames A A are arranged with their edges toward and from the interior and exterior of the vessel, and the interposed wooden frames B B entirely fill the spaces between them.

The iron and wooden frames may be bolted or otherwise secured together in pairs (one of each) before being set up to form the vessel, or each wooden frame may have an iron one bolted to each side of it before being set up. As the several frames are set up one after another they may be secured together by bolting in any suitable manner, or by short plates of iron a a notched into the outer edges of the frames and bolted thereto, as shown in Fig.

1. This framing may be covered with wooden planking G G from the keel up to such distance below the water line as it is desired to commence the armor; but the armor may be applied directly to the framing without a planking of wood.

The armor is composed of several layers of plates or flat bars of iron of the same or of different thickness, making in the aggregate the thickness required for efficient protection. In the example represented there are four layers of iron, C D E F, three of which, C D E, are in the form of broad flat bars, and the outer one, F, in the form of plates of as large size as can be conveniently rolled or forged. In the first layer the bars C C are arranged lengthwise of the vessel and bolted to the framing A B. In the second and third layers the bars D D and E E are applied diagonally to cross each other, those of one layer running in one and those of the other in the reverse direction diagonally to the bars C C, and each bar is bolted separately at as many points as may be desired through the bar or bars behind it and to the frame. The outer layer of plates, F F, is bolted through all the bars C C D D E E and through the frames. The number of layers of diagonal bars may be increased, if desirable, each layer crossing the one behind it. By this construction of the armor the armor is made to brace the framing, both diagonally and horizontally, and the several layers of the armor are made to brace each other, while by the construction of the frame of wood and iron, as desired, great strength is obtained.

The inside of the frame is planked in the usual manner, as shown at H H in Fig. 3, to form what is known as the "ceiling" or "inner skin" of the vessel; but between the port-holes K K, I propose to construct inside of the vessel solid buttresses I I of timber, as shown in Fig. 2, tapering the sides of these buttresses like the embrasures of forts. The ports J which I employ are fitted to slide up and down over the port-holes, and are made of iron of a V form in their transverse section, as shown in Figs. 1 and 4, and are beveled at top and bottom, as shown at the bottom of the port in Fig. 1, so that a projectile

striking them will not be very liable to strike them perpendicularly to their surface.

What I claim as my invention, and desire to secure by Letters Patent, is—

The combination of iron frames A A, interposed wooden frames B B, longitudinal covering bars or plates C C, reversed diagonal

bars or plates D D and E E, and covering-plates F F, substantially as and for the purpose herein specified.

WM. BALLARD.
